UNITED STATES PATENT OFFICE

GEORGE R. LUM, OF NEW YORK, N. Y., ASSIGNOR TO BELL TELEPHONE LABORATORIES, INCORPORATED, OF NEW YORK, N. Y., A CORPORATION OF NEW YORK

DESIGN FOR A DESK STAND FOR A HAND TELEPHONE

Application filed October 20, 1932. Serial No. 45,428. Term of patent 14 years.

To all whom it may concern:

Be it known that I, GEORGE R. LUM, a citizen of the United States of America, residing at New York, in the county of New York, State of New York, have invented a new, original, and ornamental Design for a Desk Stand for a Hand Telephone, of which the following is a specification, reference being had to the accompanying drawing, forming a part thereof.

Fig. 1 of the drawing is a plan view of a desk stand for a hand telephone, showing my new design;

Fig. 2 is a side elevational view; and
Fig. 3 is a front elevational view thereof.

I claim:

The ornamental design for a desk stand for a hand telephone as shown.

In witness whereof, I hereunto subscribe my name this 18th day of October, 1932.

GEORGE R. LUM.
